UNITED STATES PATENT OFFICE.

JAMES T. MATTHEWS, OF SAN ANTONIO, TEXAS.

DRAWER.

SPECIFICATION forming part of Letters Patent No. 552,441, dated December 31, 1895.

Application filed August 8, 1895. Serial No. 558,635. (No model.)

To all whom it may concern:

Be it known that I, JAMES T. MATTHEWS, of San Antonio, in the county of Bexar and State of Texas, have invented certain new and useful Improvements in Drawers; and I do hereby declare the following to be a full, clear, and exact description of the invention, such as will enable others skilled in the art to which it pertains to make and use it, reference 5 being had to the accompanying drawings, which form part of this specification.

This invention pertains to drawers, and the object of the same is to provide an improved attachment, whereby the ends of the drawer 15 must move in unison and thus avoid wedging of the drawer, which often occurs when it is moved inward and outward, and a further object is to provide a tension mechanism for the said drawer-controlling device, whereby 20 when the drawer is unlocked there will be sufficient tension upon the same to force it open, and further when the drawer is pulled outward too far the said tension device will exert an inward pull thereon and thus prevent 25 the unconscious entire withdrawal of the drawer from the bureau-case or other article of furniture or device to which it belongs.

With these objects in view my invention 30 consists in the novel features of construction hereinafter fully described and claimed, and illustrated by the accompanying drawings, in which—

Figure 1 is a front elevation of my improved 35 drawer in a suitable casing, the same being shown partly in section. Fig. 2 is a bottom plan view of the drawer when partly open, in which position the tension device is relaxed. Fig. 3 is a similar view of the drawer when pushed entirely within the case. Fig. 40 Fig. 4 is a similar view showing the same almost entirely withdrawn.

A designates the drawer proper, and B the casing in which the drawer moves. This 45 casing is here shown only for the purpose of illustrating the operation of my invention and forms no portion thereof, as the mechanism shown and presently to be described is adapted to be attached to a bureau-case or other article of furniture having sliding 50 drawers. Upon the bottom of the drawer A, and here shown near its respective ends, are the racks C, which extend parallel with the

line of movement of the drawer and which engage pinions D secured to the transverse shaft E, the latter being supported by the 55 outwardly-bent bearings F. A coiled spring G is secured at its rear end to casing B, as indicated at H, while a cord I connects the forward end of the spring with the shaft E, the cord being so connected as to wind upon the 60 shaft when the latter is revolved.

The parts are so arranged that the cord merely extends to the shaft and is not wound thereon in either direction when the drawer is partially open, as indicated in Fig. 2. An 65 inward movement of the drawer serves to wind the cord upon the shaft and thereby exert a tension thereon as the coiled spring is expanded by the operation, so that as soon as the drawer is unlocked or released the 70 tension of the spring will so rotate the shaft as to force the drawer partially open, as in Fig. 2, while if the drawer is pulled out beyond a certain limit such as will cause the cord to be wound in a reverse direction upon the 75 shaft, the coiled spring will be so expanded as to exert an inward pull upon the drawer through the medium of the pinion and rack, such as will prevent the operator from withdrawing the drawer entirely from its position 80 without considerable effort. Thus he will be warned and an entire displacement of the drawer will be avoided. It is apparent that the partial opening of the drawer when released will be of material assistance, as an 85 outward pull thereon will be unnecessary excepting when the drawer is so laden down with articles that the spring-tension will be insufficient to move it, and in such case the tension of the spring will very materially assist in the outward movement of the drawer and thus greatly reduce the amount of pull required to move it. The pinions being fixed to the shaft it is apparent that the drawer ends must move in unison, and thus all wedging 90 of the drawer either in its inward or outward movement is effectually avoided.

While I do not claim broadly the device for causing the drawer ends to move in unison for the prevention of wedging, as this 95 construction broadly stated is old, yet

What I do claim as my invention, and desire to secure by Letters Patent, is—

1. The combination of a drawer and a single

spring adapted to exert a pull upon the drawer when the latter is reciprocated in either direction from a pre-determined position so as to return the drawer to said position when released, substantially as shown and described.

5 2. The combination of a slideable drawer, a shaft adapted to be rotated by the reciprocation of the drawer, and a tension device connected to said shaft which is adapted to exert a pull upon the drawer through the medium of the shaft when the drawer is moved in either direction from a predetermined position, substantially as shown and described.

15 3. The combination of a drawer, and a tension device operating in connection with the drawer so as to hold the same normally in a given position, and which exerts a pull upon the drawer when moved in either direction from said position, substantially as shown and described.

20 4. The combination of a drawer, a shaft adapted to be rotated by the reciprocation of the drawer, a spring, and a connection between the spring and the shaft, whereby when 25 the shaft is rotated by the drawer a tension or

pull will be exerted thereon for the purpose, substantially as shown and described.

5. The combination of a drawer, a shaft adapted to be rotated by the reciprocation thereof, a coiled spring fixed at one end and 30 a cord connecting the opposite end of the spring to the shaft, whereby when the drawer is reciprocated the cord will be wound upon the shaft and the spring expanded so as to cause a pull thereon, substantially as shown 35 and described.

6. The combination of the casing, the transverse shaft supported thereby, the pinions on the ends of the shaft, the drawer, the racks thereon which engage the pinions, the spring 40 secured at one end to the casing, the cord connecting the outer end of the spring with the shaft, the parts operating substantially as herein shown and described.

In testimony whereof I affix my signature 45 in presence of two witnesses.

JAMES T. MATTHEWS.
